(57) **CLAIM**

The ornamental design for a portable computing device, as shown and described.

DESCRIPTION

FIG. 1 is a perspective view illustrating a design for a docking base portion of a portable computing device shown separated for clarity of disclosure;

FIG. 2 is a front view thereof;

FIG. 3 is a back view thereof;

FIG. 4 is a side view thereof;

FIG. 5 is another side view thereof;

FIG. 6 is a top view thereof;

FIG. 7 is a bottom view thereof;

FIG. 8 is a perspective view illustrating a design for a tablet portion of a portable computing device shown separated for clarity of disclosure;

FIG. 9 is a front view thereof;

FIG. 10 is a back view thereof;

FIG. 11 is a side view thereof;

FIG. 12 is another side view thereof;

FIG. 13 is a top view thereof;

FIG. 14 is a bottom view thereof;

FIG. 15 is a perspective view illustrating a design for a tablet portion coupled to a docking base portion of a portable computing device in a closed configuration;

FIG. 16 is a close-up perspective view of a portion thereof; and,

FIG. 17 is a side view thereof.

The broken lines and the unshaded regions bounded by broken lines of the preceding FIGURES illustrate boundaries for the FIGURES; however, the broken lines and the unshaded regions bounded by broken lines form no part of the claimed design.
